(57) **CLAIM**

The ornamental design for a forward-supporting travel cushion, as shown and described.

DESCRIPTION

FIG. 1 is a lower right front isometric view of the forward-supporting travel cushion.

FIG. 2 is a lower left rear isometric view of the forward-supporting travel cushion.

FIG. 3 is a front view of the forward-supporting travel cushion.

FIG. 4 is a rear view of the forward-supporting travel cushion.

FIG. 5 is a bottom view of the forward-supporting travel cushion.

FIG. 6 is a top view of the forward-supporting travel cushion.

FIG. 7 is a left side view of the forward-supporting travel cushion; and,

FIG. 8 is a right side view of the forward-supporting travel cushion.

1 Claim, 5 Drawing Sheets
